(57) **CLAIM**

The ornamental design for a container warming device, as shown and described.

DESCRIPTION

FIG. 1 is a top, front and right side perspective view of a container warming device, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, rear and left side perspective view thereof;

FIG. 9 is another top, front and right side perspective view of the container warming device of FIG. 1, showing a cover thereof in an open position; and,

FIG. 10 is a top, front and left side perspective view of the container warming device of FIG. 9, showing the cover in an open position.

The dashed lines formed by short segments of equal length and equal spacing shown in the figures illustrate portions of the container warming device that form no part of the claimed design.
